UNITED STATES PATENT OFFICE

CLARENCE T. HOLLINGSWORTH, OF DETROIT, MICHIGAN, ASSIGNOR TO BULLDOG ELECTRIC PRODUCTS COMPANY, OF DETROIT, MICHIGAN, A CORPORATION OF WEST VIRGINIA

DESIGN FOR AN ELECTRIC CONTROL PANEL BOARD

Application filed November 24, 1930. Serial No. 37,770. Term of patent 7 years.

To all whom it may concern:

Be it known that I, CLARENCE T. HOLLINGSWORTH, a citizen of the United States, residing at Detroit, in the county of Wayne and State of Michigan, have invented a new, original, and ornamental Design for Electric Control Panel Board, of which the following is a specification, reference being had to the accompanying drawing, forming part thereof.

Fig. 1 is a front elevation of the electric control panel board showing my new design.

Fig. 2 is a perspective view of a section thereof.

I claim:

The ornamental design for an electric control panel board substantially as shown.

CLARENCE T. HOLLINGSWORTH.
